UNITED STATES PATENT OFFICE.

GAYNIE L. PRELLER, OF AUGUSTA, ARKANSAS.

SHUTTLE.

1,185,534.

Specification of Letters Patent. Patented May 30, 1916.

Application filed April 23, 1915. Serial No. 23,417.

To all whom it may concern:

Be it known that I, GAYNIE L. PRELLER, a citizen of the United States, residing at Augusta, in the county of Woodruff and State of Arkansas, have invented new and useful Improvements in Shuttles, of which the following is a specification.

This invention relates to shuttles and more particularly to tatting shuttles.

10 In this type of work it is necessary frequently to connect certain portions of the chains formed in the manipulation of the shuttle to other chains and to do this the operator must use a pointed instrument of 15 some character, preferably one having a hook on the end like a crochet or knitting needle. It is also necessary to untie knots which are made in error and when these loop-forming and knot-untangling instruments 20 are separate from the shuttle they are generally difficult to find when needed.

It is therefore the object of this invention to avoid these difficulties and to provide a tatting shuttle having suitable instruments 25 associated therewith for forming a proper connecting loop and for untangling knots.

Another object of the invention is to provide a tatting shuttle having a slidably mounted knot loosening or untangling member 30 and a slidably mounted loop-forming member, the operative ends of which instruments may be projected beyond the ends of the shuttle and which are normally retained in grooves in such a manner that they will 35 be substantially sealed or protected from engagement with the threads of the lace as the shuttle is operated in the usual manner.

It is another object of the invention to provide a shuttle of this character for 40 needles having associated therewith a needle that forms a continuation of the shuttle when projected and a guide therefor in passing the shuttle through the loop.

Further objects of the invention will appear as the following specific description 45 is read in connection with the drawings which form a part of this application and in which:—

Figure 1 is a perspective view, Fig. 2 is 50 a longitudinal section taken through the shuttle, Fig. 3 is a detail plan view showing one of the instruments in projected position.

Referring more particularly to the drawings 1 represents a mounting block around 55 which the thread is wound and secured to the sides of the block in any preferred man-

ner are the side plates 2 and 3 pointed at opposite ends in the customary manner to facilitate the passage of the shuttle through the loops of the lace. The block 1 is provided with longitudinal grooves 4 upon opposite sides and the underside of each side plate 2 and 3 is provided with a longitudinal channel 5 which terminates at one end in an aperture passing diagonally through the thickness of the side plates and communicating with the groove 7 forming in the outer face of the side plate adjacent its pointed end. Mounted in the grooves 4 and 5 and having one terminal arranged to project through the aperture 6 and lie within the groove 7 are the loop-forming and knot-untangling instruments 8 and 9. The instrument 9 has one end pointed like a needle or pin and lying in the groove 7 when in inactive position while the instrument 8 has the hook end in the form of a crochet needle which also lies in its groove 7 when in inactive position. Each side plate as shown is provided with a longitudinal slot 10 which exposes the instruments 8 and 9 as shown and each instrument is provided with a laterally extending lug 11 which travels in the slot 10 and is arranged to be engaged by the finger nail so that the instrument 35 may be readily moved back and forth in the grooves to project its operative end beyond the end of the shuttle to throw the instrument into operative or inoperative position as is desired. When the instruments are withdrawn so that their points are within the groove 7 the points will be arranged below the outer surfaces of the plates and thus do not interfere with the passage of the shuttle through the loops of 95 the lace. As stated, the instrument 9 is used solely for the purpose of loosening knots which are made in error.

The instrument 8 is used in the ordinary manner of a crochet needle in forming loops and when thus used has its hook pass through the loop thereby forming a starting point for the shuttle in its passage through the loop.

What is claimed is:—

A tatting shuttle comprising a spacing block having arcuate spaced grooves in opposite sides thereof, side plates secured to the spacing block and having internally arranged grooves, said plates having an aperture and an exteriorly arranged groove communicating with said aperture, an in-

strument slidably mounted within the grooves and passing through the apertures and having their opposite ends normally seated in the grooves on the external faces of the side plates and means for projecting and retracting said instrument, said external grooves and apertures being arranged in a plane between the grooves of said block

for frictionally holding said instruments in either of their two positions.

In testimony whereof I affix my signature in presence of two witnesses.

GAYNIE L. PRELLER.
